UNITED STATES PATENT OFFICE.

MORRIS S. BROADT, OF EAST DOWNTON, PENNSYLVANIA.

HUMIDOR.

1,120,180.

Specification of Letters Patent.

Patented Dec. 8, 1914.

Application filed May 4, 1914. Serial No. 836,369.

To all whom it may concern:

Be it known that I, MORRIS S. BROADT, a citizen of the United States, residing at East Downingtown, in the county of Chester and State of Pennsylvania, have invented a new and useful Humidor, of which the following is a specification.

This invention relates to improvements in humidors.

10 An object of the present invention is to provide a humidor which being of simple arrangement and construction may be cheaply manufactured and will be at the same time, capable of receiving and maintaining in good condition, cigars and the like, for a considerable period of time.

15 A further object is to provide a humidor embodying a novel and advantageous form of sponge holder, by means of which, a large sponge or similar absorbent material is securely held in proper position and in such condition as to absorb and retain moisture for a considerable period of time.

20 With the foregoing and other objects in view which will appear as the description proceeds, the invention resides in the combination and arrangement of parts and in the details of construction hereinafter described and claimed, it being understood 25 that changes in the precise embodiment of the invention herein disclosed, can be made within the scope of what is claimed, without departing from the spirit of the invention.

30 In the drawings accompanying this specification and forming a part thereof, the preferred embodiment of my invention is illustrated, in which:-

35 Figure 1 is a view longitudinal section of my improved humidor. Fig. 2 is a cross sectional view thereof, taken on the line 2-2 of Fig. 1.

40 Referring to the drawings in which similar reference numerals designate corresponding parts throughout the several views, the open ended receptacle 3 has the outturned beads 4 and 5 adjacent its upper and lower extremities and a third bead 6 there-intermediate. The receptacle 3 may 45 be of any preferred cross sectional contour and in the present drawings has been represented as cylindrical, the same being the conventional type.

45 A lid 7 extends down over the upper extremity of the receptacle and contacts with the bead 4 and is resiliently held so posi-

tioned. A reticulated or foraminous transverse partition 8 is forced within the receptacle until it encounters the channel 9 defined by the bead 6, into which it immediately springs and becomes accordingly held against displacement. In this connection it is to be noted that the apertures with which the transverse partition 8 is provided allows the partition to be more or less compressed, which, when taken in connection with the expansive resiliency of the walls of the receptacle 3 and the slight channel 9 provides that the transverse partition 8 after assuming its final position will be held 60 against rattling. The space between the partition 8 and top 7 is sufficient to receive cigars and allied material therebetween for the retention of the same in proper condition.

65 Fitting over the lower extremity of the receptacle and contacting with the bead 5 is the lower cover 10 which in addition to closing the lower extremity of the receptacle constitutes a part of the absorbent material 80 or sponge retainer. A pair of arms 11 are rigidly secured at their lower extremities to the cover 10 at diametric points and converge upwardly therefrom and are joined at their upper extremities by the short transverse bar 12. A plate 13 is rigidly secured as at 14 to the bar 12 and is of relatively less diameter than the diameter of the receptacle so as to stop short of the side walls thereof as illustrated in Fig. 1. The said 90 plate is provided with the downwardly extending marginal flange 14 which curves slightly inwardly, which marginal flange engages a sponge 15 and holds the same against shifting in a lateral or transverse 95 direction. The sponge 15 is disposed beneath the arms 11 and bar 12 which, in addition to the holding action of the downwardly and inwardly extending marginal flange 14, holds the sponge from shifting 100 and thus out of contact with the walls of the receptacle. The fact that the sponge or absorbent material 15 is so held is of importance, as will be readily appreciated when it is noted that the humidor is moved 105 about during use which tends to shake and dislodge the absorbent material. The manner in which the sponge is held provides a large exposed area, providing for the maintenance of the proper humidity within the 110 receptacle. The sponge is of such size as to absorb a quantity of water sufficient to

maintain the desired humidity within the receptacle for a considerable period of time.

What is claimed is:—

1. A humidor comprising a receptacle, a lower cover therefor, a transversely extending plate carried thereby and relatively smaller than said receptacle, said plate being provided with a downwardly extending marginal flange, and a foraminous partition carried by the receptacle and spaced a distance above the first mentioned plate.
2. A humidor comprising an open ended receptacle, upper and lower covers therefor, said receptacle being provided with an outwardly bent bead intermediate its ends, a

reticulated or foraminous partition disposed within and carried by said bead, a pair of upwardly converging arms carried by the lower cover, a transverse plate carried by said arms and provided with a downwardly and slightly inturned marginal flange for the reception and retention of a sponge or absorbent material therebeneath.

In testimony that I claim the foregoing as my own, I have hereto affixed my signature in the presence of two witnesses.

MORRIS S. BROADY.
